UNITED STATES PATENT OFFICE

2,441,256

DEEP WELL PUMPING UNIT

William F. Brown, Crescent, Okla.

Application June 14, 1946, Serial No. 676,775

5 Claims. (Cl. 74—44)

1

This invention relates to an improved construction of pumping unit used with deep well oil pumps and has for its primary object to provide a unit similar to that disclosed in my co-pending application for U. S. Letters Patent, entitled Walking beam, filed April 12, 1946, and bearing Serial No. 661,839.

The present invention is for the same purpose as the invention of the aforementioned application and differs therefrom in that provision of a pivotally mounted walking beam is dispensed with.

The primary object of the present invention is to provide a deep well pumping unit that may be operated with a minimum of power and which will be especially efficient for use with wells of great depth.

A further object of the invention is to provide a supporting beam forming a part of the pump unit and which is normally maintained in a fixed position from which it is capable of being readily released and swung to a position in which it will not interfere with the removal of pump rods or pump tubing from an oil well.

A further aim of the invention is to provide a normally fixed supporting beam possessing sufficient resiliency to cushion the parts at the instant that the direction of movement of the pump rod is reversed.

Other objects and advantages of the invention will hereinafter become more fully apparent from the following description of the drawings, which illustrate a preferred embodiment thereof, and wherein:

Figure 1 is a side elevational view of the improved deep well pumping unit;

Figure 2 is a horizontal sectional view thereof taken substantially along a plane as indicated by the line 2—2 of Figure 1;

Figure 3 is a transverse vertical sectional view taken substantially along a plane as indicated by the line 3—3 of Figure 1;

Figure 4 is an end view in elevation of the unit with the cables removed therefrom;

Figure 5 is a transverse vertical sectional view taken substantially along a plane as indicated by the line 5—5 of Figure 1;

Figure 6 is a horizontal sectional view taken substantially along a plane as indicated by the line 6—6 of Figure 1;

Figure 7 is a fragmentary side-elevational view, partly in vertical section of a portion of the unit;

Figure 8 is a similar view of another portion thereof, and

Figure 9 is a cross sectional view taken sub-

2

stantially along a plane as indicated by the line 9—9 of Figure 8.

Referring more specifically to the drawings, a deep well pumping unit in its entirety is designated generally 10 and includes an upright supporting frame, designated generally 11 and which includes upwardly and inwardly inclined corner posts 12, a top or platform 13 which is supported thereby, an upright jack post 14 and horizontal braces 15.

A pair of fulcrum brackets 16 are bolted to the upper side of the platform 13 and are adapted to engage in recesses of bifurcated fulcrum members 17 which depend from a supporting beam 18, as seen in Figure 5. The members 16 and 17 are provided with aligned openings for receiving a pivot pin 19 which extends therethrough and by means of which the beam 18 is pivotally supported on and above the frame 11.

The beam 18 is formed of laterally spaced channel members 20 which are arranged with the channel portion thereof opening outwardly of one another and in laterally spaced apart relationship.

A pin or shaft 21 extends through intermediate portions of the channel member 20, adjacent one end of the beam 18 to provide a journal for a pair of pulleys 22 which are journaled thereon and disposed between the channel members 20.

As best seen in Figures 5 and 6, a shaft or axle 23 extends through the intermediate portion of the opposite ends of the channel members 20 and through bearing blocks 24, mounted in the channel portions thereof at the opposite end of the beam 18. A pair of pulleys 25 are journaled on the shaft 23 and disposed between said last mentioned ends of the channel members 20. The channel members 20 are provided with downwardly opening sockets 26 at each end thereof provided to receive ball joints 27 formed on corresponding ends of rigid braces 28. The opposite ends of the braces 28 are pivotally connected by tapered pins 29 to bifurcated brackets 30, one of which is fastened to each of the corner posts 12, adjacent the lower ends thereof. It will thus be seen that the four braces 28 normally function to support the beam 18 in a rigid horizontal position above and at a right angle to the vertical axis of the plane 11.

The pulleys 22 are located substantially over the upper end of the well tubing 31 of an oil well from the upper end of which well tubing 31 projects a pump rod 32. A cable or other flexible member 33 is trained over each of the aligned pulleys 22 and 25; said cables having correspond-

55 pulleys 22 and 25; said cables having correspond-

ing ends which are connected by fastenings 34 to the upper end of the pump rod 32. The opposite ends of the cables 33 are connected to the socket portion of an eye member 35, the eye of which turnably engages a pin or sub-shaft 36 which projects outwardly from one side of a substantially semi-circular counter-weight 37 which is keyed to an end of a crank or driven shaft 38. The crank or driven shaft 38 terminates at the side of a counterweight 37 from which the sub-shaft 36 projects so as not to interfere with the cables 33 when the counterweight 37 is revolved. The sub-shaft 36 is disposed concentric with the outer edge of the counter-weight 37.

From the foregoing it will be readily apparent that by providing a counter-weight 37 which substantially equals the weight of the pump rod 32, the pump rod 32 can be reciprocated by the deep well pumping unit 10 with very little power required. The shaft 38 is driven in any suitable manner and from any suitable source of power and it will be readily apparent that in moving in either direction from its upper dead center position, as seen in Figure 1, it will exert a pull on cables 33 to raise the pump rod 32 until the counterweight 37 is moved through an arc of substantially 180°. During this movement, gravity pull exerted by the counterweight 37 will counterbalance the weight of the pump rod 32 until the counter-weight has reached its lower dead center position. After being moved therebeyond by the driven shaft 38 the downward pull exerted by the pump rod 32 will overcome the weight of the counter-weight 37 so that the shaft 38 will be revolved with a substantially uniform load thereon and with a very small amount of power required.

The supporting beam 18 and the braces 28 possess sufficient resiliency to cushion the pump rod 32 at the instant that the direction of its movement is reversed. The outer portion of the peripheries of the pulleys 22 are at all times located directly above the well tubing 31 so that the pull on the pump rod 32 is in a direction axially of the well tubing 31.

To facilitate tensioning of cables 33 and to eliminate any slack existing therein, two pairs of grooved pulleys 39 are journaled between and above the pulleys 22 and 25 by brackets or bars 40. The brackets 40 are provided with vertical slots 41 for adjustably receiving nut and bolt clamping fastenings 42 which project laterally from the beam members 20 and by which the brackets 40 and pulleys 39 are adjustably supported relatively to the beam 18. The cables 33 are trained over the pulleys 39 which may be adjusted toward and away from the beam 18 for varying the tension of the cables 33.

To remove the pump rod 32 and the well tubing 31, the upper end of the pump rod 32 is engaged and the cables 33 are detached therefrom after which the tapered pins 29 are removed to disconnect the braces 28 from the frame 12. The beam 18 can then be swung to move the pulleys

22 and the end of the beam in which said pulleys are disposed out of a position above the well tubing to facilitate the removal of the pump rod or the pump rod and well tubing.

Various modifications and changes are contemplated and may obviously be resorted to without departing from the spirit and scope of the invention as hereinafter defined by the patent claims.

I claim:

1. In a deep well pumping unit, an upright supporting frame, a horizontal beam fulcrumed intermediate of its ends on the supporting frame, braces supported by said frame and connected to the ends of the beam for maintaining said beam

15 in a horizontal position, pulleys journaled in the ends of said beam, a cable trained over said pulleys and having one end adapted to be connected to a pump rod disposed directly beneath the outer portion of one of said pulleys, and the opposite end of said cable being eccentrically connected to a driven rotatable counter-weight.

2. A deep well pumping unit as in claim 1, said braces being detachably connected to the frame and pivotally connected by ball and socket connections to the ends of the beam.

3. In a deep well pumping unit as in claim 1, said beam being formed of laterally spaced channel irons, and said pulleys being journaled between the ends of said channel irons.

30 4. A deep well pumping unit comprising an upright supporting frame, a beam fulcrumed thereon and supported thereabove and at right angles thereto, pulleys journaled in each of the ends of said beam, cables trained over said pulleys and having corresponding ends connected to a deep well pump rod, disposed beneath one end of the beam, a driven eccentric counter-weight disposed beneath the other end of the said beam and pivotally and eccentrically connected to the opposite ends of said cables, and detachable means for maintaining said beam in substantially a horizontal position.

35 5. A deep well pumping unit as in claim 4, said detachable means comprising a plurality of diagonal braces having lower ends detachably connected to corner posts of the frame, said braces having ball portions on their opposite ends, and socket members secured to the ends of said beams for receiving and forming a universal connection with said ball portions, whereby when said first mentioned ends of the braces are detached from the frame said beam may be swung to a position out of the upward path of movement of the pump rod or the pump tubing containing said rod.
